UNITED STATES PATENT OFFICE

SAMUEL GIBBONS, OF BINGHAMTON, NEW YORK, ASSIGNOR TO THE
EXCELSIOR OIL-MANUFACTURING COMPANY.

IMPROVEMENT IN STILLS FOR REFINING AND DISTILLING OILS.

Specification forming part of Letters Patent No. 85,810, dated January 12, 1869.

To all whom it may concern:

Be it known that I, SAMUEL GIBBONS, of Binghamton, in the county of Broome, and in the State of New York, have invented certain new and useful Improvements in Stills for Refining and Distilling Oils; and do hereby declare that the following is a full, clear, and exact description thereof, reference being had to the annexed drawings, making a part of these specifications.

a m represent retorts or stills; *b*, supply-pipes; *d d*, the upper surface of chamber *h h*; *e*, vapor-pipe to condenser *f*; *g h r*, discharge-pipes; *i*, conducting-pipe from still *a* to still *m*; *j x*, perpendicular chambers; *k k*, perforated cross-pipes; *l l*, steam-pump or injector; *n*, vapor-pipe from still *m*; *o*, discharge-pipe from chamber *h h*; *s*, water-supply pipe to, and *t* discharge-pipe from, condenser *f*; *u*, partition in chamber *h h*; *v*, valve; *w*, steam-pipe; *y*, horizontal supply-pipe.

Figure 1 is an end elevation closed; Figs. 2 and 4, horizontal sectional views; Fig. 3, end elevation opened.

In this new process of refining and distilling, the crude oil is admitted into still *a* through pipe *b*, when it passes over the outer surface of chamber *h h*, the radiated heat from which vaporizes the lighter portion of the oil, which is then carried through the pipe *e* into the condenser *f*, where it is condensed, and discharged through pipe *g* in the form of naphtha or benzine. That portion of the oil not vaporized in passing over the heated surface of the chamber *h h* passes from the bottom of the still *a* through the pipe *i* into the chamber *j*, thence rises, and another portion of oil is vaporized by passing over or under sprays of steam ejected from the pipes *k k* in still *m*, as shown in Fig. 2, or the oil is introduced directly from still *a* through pipe *i* into the steam-pipe *w*, when it is vaporized by being forced through the perforated pipes *k k* by means of an injector or steam-pump, *l l*, Fig. 4. The hot vapor and steam then pass from still *m* through the vapor-pipe *n* into the horizontal chamber *h h*. This chamber is provided with a partition, *u*, or pipe *n*, so arranged as to keep a continuous current of hot steam and vapor passing in and out, so producing and utilizing an amount of heat, which would otherwise be lost, sufficient

to vaporize a portion of the oil on its first introduction into the still *a*. From the chamber *h h* the vapor and steam pass out at pipe *o* and into the condenser *f*, and, being there condensed, is discharged from pipe *k* in the form of kerosene-oil.

The degree of heat required in chamber *h h* is regulated by means of valve *v* in pipe *n*.

That portion of oil not vaporized by the above-described process passes from still *m* into chamber *x*, and is discharged from pipe *r* in the form of marketable oil.

If the upper surface of chamber *h h* be smooth, the crude oil is introduced and distributed over the same by means of the perforated pipe *y*, Fig. 4. If corrugated or grooved, the oil is introduced directly from pipe *b*, as shown in Fig. 2.

The marked advantages secured by this improved process of refining oils are, first, the production of a superior article; second, greatly increased production; third, rapidity of operation; fourth, a material reduction in the cost of labor and fuel.

I am aware that oil has been distilled by passing it in a thin stratum over the bottom of the still, which is heated beneath or around its exterior.

I am also aware that the carrying off of vapors of oil by means of a jet or blast of steam or air is not new, nor the removing of the light from the heavy parts of petroleum by such jets; nor do I claim the use of vapor while passing through the condenser for heating the oil on its passage into the still.

I admit my oil cold into the still in a body, and it passes through the still, being vaporized entirely by steam both directly and indirectly applied.

It will be seen, by my process, that the vapor formed in the still *m* rises through the goose-neck *n*, and is then passed into the chamber *h*, and from thence back into the still *m*, thereby assisting materially in distillation. By my process the oil is admitted directly into the still without the aid of pressure or a forcing apparatus of any form, as there is no interruption in the form of steam or other obstruction to prevent its free ingress.

I do not spray the oil, but allow it to pass in volume through both the pipe and still,

thereby enabling the distillation of a great quantity of oil at one time, and very rapidly.

In admitting the oil on the plate *d* and through the steam-chamber above I am enabled to combine the distillation process of both steam and heat. The vapor and steam in the chamber *h* and steam in the still *a* cause the partial distillation of oil in the upper still before its passage to the lower one.

It will be understood, of course, that the stills *a* and *m* may be in one case with a division-plate, or they may be separated, as shown in the drawings.

After the oil, partially distilled, has passed into the lower still, *m*, it is there acted upon by the steam in the form of spray, passing through the spray-openings in the cross-pipes *k* on the steam-pipe *w*. These spray-openings are used in contradistinction to steam-jets, so as to vaporize the oil, and not agitate the same on its passage in a body through the still. By these means I produce an oil in an uncolored or nearly white state.

The injector *l* at the end of the pipe *w* can be used for injecting either steam or air into the oil for vaporizing the same.

What I claim is—

1. The use of vapor and steam combined, which arise during distillation from the lower still, *m*, for the purpose of heating the chamber *h* in the upper still, *a*, to assist in evaporating the lighter portions of oil on its first introduction in volume into the still, substantially as set forth.

2. The vaporization of oil by passing it in volume over or under sprays of steam, substantially in the manner specified.

3. The steam and vapor chamber *h*, arranged within the still *a*, substantially as and for the purposes set forth.

4. The combination of the chamber *h*, diaphragm *u*, and pipes *n* and *i*, with the still *a*, substantially as set forth.

5. In combination with the pipe *w* and its spray-pipes *k*, the injector *l*, substantially as and for the purposes set forth.

6. The within-described process for refining oils, substantially as specified.

7. Applying the steam for vaporizing over or above the body of the oil, so as to heat it without agitation, and prevent carrying over the unvaporized particles of oil, substantially as specified.

In testimony that I claim the foregoing I have hereunto set my hand this 21st day of November, 1867.

SAML. GIBBONS.
